Primary Examiner — Anhdao Doan*Assistant Examiner* — Mary Shannon Malley(57) **CLAIM**

The ornamental design for a track for a diagnostic system, as shown and described.

DESCRIPTION

FIG. 1 is a perspective view of a track for a diagnostic system in accordance with my new design;

FIG. 2 is a front elevational view thereof;

FIG. 3 is a cross-sectional view of the track taken along line 3-3 of FIG. 1;

FIG. 4 is a rear elevational view of the track for a diagnostic system of FIG. 1;

FIG. 5 is a left side elevational view thereof;

FIG. 6 is a right side elevational view thereof;

FIG. 7 is a top view thereof;

FIG. 8 is a bottom view;

FIG. 9 is a perspective view thereof with the track for diagnostic system shown in an in vitro diagnostic system;

FIG. 10 is a top view thereof; and,

FIG. 11 is a close up view of the circle section of FIG. 1, which shows details which are exemplary of similar details throughout the various views.

The broken lines showing an in vitro diagnostic system represent environmental subject matter that forms no part of the claimed design. All other broken lines show portions of the track for a diagnostic system that form no part of the claimed design.
